Primary Examiner—Jennifer Rivard*Assistant Examiner*—Angela J Lee(74) *Attorney, Agent, or Firm*—Sughrue Mion, PLLC(57) **CLAIM**

The ornamental design for a display, as shown and described.

DESCRIPTION

FIG. 1 is a front, right side, top perspective view of a display showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged partial view thereof, taken along line 8—8 of FIG. 2; and,

FIG. 9 is a cross-sectional view thereof, taken along line 9—9 of FIG. 8.

The portions of the display in broken lines are shown for illustrative purposes only and form no part of the claimed design.
